POTENTIOMETER

Joseph G. Brady, Minneapolis, and Clyde H. Jackson, St. Paul, Minn., assignors to Minneapolis-Honeywell Regulator Company, Minneapolis, Minn., a corporation of Delaware

Application May 15, 1950, Serial No. 162,016

6 Claims. (Cl. 201—56)

1

This invention relates to potentiometers and specifically to non-inductive wire wound potentiometers. It is therefore an object of the invention to provide a new and improved type of non-inductive wire wound potentiometer.

Another object of the invention is to provide a non-inductive wire wound potentiometer in which the wiper arm may engage all the turns of the resistance winding portion.

Non-inductive potentiometers may be used to particular advantage in alternating voltage circuits in that there is no reactance across the potentiometer. As a result, there would be no phase shift in the voltage across the potentiometer which might be detrimental to the operation of the system. Further, such a non-inductive potentiometer could be used in a circuit wherein the alternating voltages vary over a range of frequencies without the effective impedance of the potentiometer changing. Because there would be no inductance in the potentiometer, there would be no reactance and the only impedance would be resistive, which does not change with change in frequency.

In one embodiment of the invention, the resistance unit for the potentiometer comprises a single layer of wire of very low resistance and an overlying layer of high resistance wire, the two layers being wound so that their inductive effects are in opposition and substantially cancel each other out. The two windings are connected together at one end and the opposite ends of the two windings serve as the two terminals of the resistance unit. The relative resistance of the two windings is such that a very high percentage of the total voltage drop is across the outer layer, and consequently, a wiper arm adjustable over the outer layer may select substantially any percentage of the terminal voltage.

The resistance unit for the potentiometer may also be made by first connecting one end of the conductor to one end of the resistance wire and then winding the conductor and resistance wire on the core together so that the turns on each side of the resistance wire are composed of the conductor and vice versa. Here again the turns of the conductor and resistance wire are parallel. In this case the resistance wire must be of larger diameter than the conductor in order that the portion of the turns of the resistance wire engaged by the wiper arm will be above the turns of the conductor so that the wiper arm will make contact only with the resistance wire.

Non-inductive potentiometers have been known in the art but prior to the present invention all

2

such potentiometers used resistance wire for both windings on the core and as a result, the voltage obtainable on the wiper arm of the potentiometer was variable over only half the range of the voltage between the terminals of the potentiometer. By use of the potentiometer herein disclosed, the voltage obtainable on the wiper arm is capable of varying over substantially the entire range of the voltage impressed across the potentiometer terminals. This results in a much more usable potentiometer and also requires only about half as much voltage on the terminals for the same voltage output as would be required for potentiometers heretofore known.

For a better understanding of the invention reference is had to the following detailed description taken in conjunction with the accompanying drawing in which

Figure 1 shows, partly in cross-section, one form of the complete resistance unit for the potentiometer;

Figure 2 shows the resistance unit of Figure 1 in the process of being wound;

Figure 3 shows the resistance unit of Figure 1 farther along in the process of being wound than as shown in Figure 2;

Figure 4 shows a modification, partly in cross-section, of the resistance unit for the potentiometer; and

Figure 5 shows the resistance unit of Figure 4 in the process of being wound.

In the resistance unit of Figure 1, a core 10 of insulating material shown to have a first layer of winding composed of a conductor 11 with one end 12 of the conductor being connected, as by a soldered connection 13 to a resistance wire 14 which is wound back over the conductor winding. The end 15 of conductor 11, which is opposite to soldered end 12 and connection 13 of the resistance winding opposite the soldered end 13 extend from the potentiometer and may be connected across a voltage source to impress a voltage across the conductor and resistor windings. A wiper arm 17 makes contact with the resistance winding and is movable across the entire length of the resistor winding of the potentiometer.

For purposes of illustration, the size of the wire with relation to the diameter of the core has been greatly exaggerated, and the number of turns has been greatly reduced. In actual practice, the ratio of coil diameter to wire diameter will be so large that the difference in diameters of the inner and outer layer will produce little difference in inductance of the two coils. However, if necessary, the inner layer may be continued beyond

the outer layer a short distance to bring its inductance up to that of the outer layer.

This resistance unit of the potentiometer may be wound by fastening the free end of the conductor to the core and then rotating the core, as is shown in Figure 2, and winding the conductor 11 upon the core such that the adjacent turns of the conductor rest against each other. The conductor must have an insulation, perhaps of varnish, so that electrical contact is not made between the adjacent turns but that any current which passes through the conductor must of necessity flow along the conductor. The resistance wire must also be insulated in order that the current which flows through the resistance wire does not travel from turn to turn but must rather flow along the resistance winding.

After the conductor is completely wound on the core it is connected to the resistance wire 14 and the connection is then fastened to the core. The core is then rotated in the reverse direction and the resistance wire is wound on the core back over the conductor until the resistance wire is wound over the length of the core. The end of the resistance wire may then be fastened to the core in any desirable manner in order that the wire may not be unwound from the core. When the potentiometer is completely wound, a surface of the resistance wire winding is then cleaned in order that the wiper arm may make contact with the bare resistance wire. Obviously, the resistance wire is not cleaned to such an extent that the adjacent turns of the resistance wire may make electrical contact with the other but is only cleaned sufficiently to permit the wiper arm to make electrical contact with the turns.

In order to show how this type of winding eliminates inductance effect of the potentiometer let it be assumed that an alternating voltage is placed across terminals 15 and 16 of the conductor and resistance wires respectively and then consider what happens on the half cycle when the conductor terminal 15 is positive with respect to resistance wire terminal 16. It can be seen by a simple application of the right hand rule where the fingers point in the direction of current flow and the thumb points in the direction of the magnetic flux that to determine the direction of the magnetic flux through the conductor the fingers will extend up behind the potentiometer, as it is shown in Figure 1 and the thumb will then be pointing toward the right. The current flow in the resistance wire on the other hand, will be flowing, during this half cycle, such that the fingers of the right hand are extended downwardly behind the potentiometer with the thumb then pointing toward the left. Thus the magnetic fluxes from the conductor and from the resistance wire are directly opposing each other and the magnetic fluxes are cancelled out. On the next half cycle the current flow through the conductor is in the opposite direction so that the magnetic flux will be toward the left. The current flow through the resistance wire is also in the opposite direction and the resulting magnetic flux will be toward the right and the magnetic fluxes will again cancel each other out. Thus, a non-inductive potentiometer has been produced.

Because half of the windings on the core are made from a conductor rather than all of the windings being composed of the resistance wire, virtually the entire voltage impressed across terminals 15 and 16 of the conductor and resistance wire is across the resistance wire which is contacted by wiper arm 17. Thus, almost any portion

of the voltage across terminals 15 and 16 may be picked off by the wiper arm. If the entire windings were made from the resistance wire, the first layer of windings would be completely covered by the second layer and the wiper arms could not make contact to the first layer. Thus, the wiper arm 17 could pick off only from half of the voltage across terminals 15 and 16 to all of the voltage across these two terminals, if the voltage picked off were between terminal 15 and wiper arm 17, or, the voltage picked off by the wiper arm would be between zero voltage and a half of the voltage impressed between terminals 15 and 16 if the voltage picked off were the voltage between terminal 16 and wiper arm 17. If, then, it were desired that the wiper arm be able to pick off voltages up to a certain maximum voltage it would be necessary to impress twice that voltage across the terminal, resulting in the use of higher voltages in the circuit. Because of the possibility of electrical shocks, arcings, etc., it is good practice to keep voltages in a circuit as low as possible in conformance with good performance by the circuit.

If desired, the resistance unit of the potentiometer may be wound as shown in Figures 4 and 5. In this case the core 10 has both the conductor and the resistance wire wound on the core at the same time. In the modification shown in Figure 4 the conductor 11a and resistance wire 14 are soldered together, as at 20, with these terminals then fastened to the core. As better shown in Figure 5, the core is then rotated and the conductor and resistance wire are fed onto the core such that the alternate turns are composed of conductor, resistance wire, conductor, resistance wire, etc. In this case, because the conductor and resistance wire both lie against the core and the turns are alternately resistance wire, conductor, etc. it is necessary that the conductor 11a be of smaller diameter than the resistance wire 14 in order that the wiper arm 17 will make contact only with the resistance wire. Obviously, the conductor and resistance wire are again insulated so that there is no electrical contact between the adjacent turns. When the conductor and resistance wire have been completely wound on the core 10, they are fastened to the core by any satisfactory means and the terminals 15a and 16 extend from the resistance unit. Again, one surface of the resistance wire is cleaned so that the wiper arm 17 may make contact with the turns of the resistance wire to pick off a voltage therefrom.

It can be seen that here again the windings of the conductor and resistance wire are opposite with respect to each other in that the windings are parallel with respect to each other and the current flow through the turns is in the opposite direction. In this case the resistance wire must have a larger diameter than the conductor in order that the wiper arm will not make contact with the conductor but only to the resistance wire. If the wiper arm were to make contact with the conductor it would, in time, scrape off the insulation on the conductor and thus make electrical contact with the conductor. The wiper arm is, of course, broad enough so as to make contact with two adjacent turns of the resistance wire simultaneously in order that the change in voltage picked off by the wiper arm changes smoothly with movement of the wiper arm along the resistance unit.

In order to show how the non-inductance is achieved in the potentiometer resistance unit as shown in Figure 4 let it be assumed that an

alternating voltage is impressed across terminals 15a and 16 of the conductor and resistance wire respectively and let the situation be considered on the half cycle that terminal 15a of the conductor is positive with respect to terminal 16 of the resistance wire. On this half cycle by a simple use again of the right-hand rule the fingers of the hand will point down behind the potentiometer for the current flowing through the conductor with the thumb pointing toward the left. The current flow through the resistance wire will be upwardly behind the potentiometer and the thumb will point toward the right. Thus, the magnetic flux moving toward the left due to the current flowing through the conductor and the magnetic flux moving toward the right due to the current flowing through the resistance wire will cancel each other out and a non-inductive potentiometer results. On the next half cycle, of course, the magnetic fluxes due to the conductor and the resistance wire are in the opposite directions and will again cancel each other out.

In the potentiometers as shown in Figures 4 and 5 it is necessary to rotate the core in only one direction in order to wind both the conductor and the resistance wires on the core. It is not possible with this potentiometer resistance unit to place as many turns of the resistance wire on the core as is possible in the resistance unit as shown in Figure 1 and so a larger voltage drop is present across each turn of the winding of the unit of Figure 4 than there is across each turn of the unit shown in Figure 1, assuming in each case that the same magnitude of voltages is impressed across the terminals 15 and 16.

In the modification shown in Figure 4 it is also true, as was pointed out for the modification of Figure 1, that virtually the entire voltage drop impressed across terminals 15 and 16 is across the resistance wire to which contact is made by the wiper arm 17.

While two desired forms of the invention have been shown and described, modifications within the spirit of the invention could be made by those skilled in the art and it is therefore to be understood that the invention is to be defined and limited only to the extent of the appended claims.

We claim as our invention:

1. A potentiometer having an electrical conductor of comparatively low resistance wound in a first direction, a resistance wire of comparatively high resistance wound in the opposite direction over said conductor such that the turns of the resistance wire are substantially parallel to the turns of the conductor, one end of the conductor being connected to one end of the wire, and a wiper arm making contact only with said resistance wire.

2. A potentiometer having a core, an electrical conductor of comparatively low resistance wound about said core in a first direction, a resistance wire of comparatively high resistance having one end connected to one end of said conductor and wound about said core in the opposite direction such that the turns of the resistance wire are

substantially parallel to the turns of the conductor, and a wiper arm making contact only with said resistance wire.

3. A potentiometer having an electrical conductor of comparatively low resistance wound in a first direction, a resistance wire of comparatively high resistance having one end connected to one end of the conductor and wound in the opposite direction along said conductor such that the turns of the resistance wire are substantially parallel to the turns of the conductor, and a wiper arm making contact only with said resistance wire.

4. A potentiometer having an electrical conductor of comparatively low resistance wound in a first direction about an insulated core, a resistance wire of comparatively high resistance having one end connected to one end of the conductor and wound in the opposite direction about the core, the number of turns of the resistance wire being the same as the number of turns of the conductor, and a wiper arm making contact only with said resistance wire.

5. A winding for a potentiometer having an electrical conductor of comparatively low resistance wound in a first direction; a resistance wire of comparatively high resistance having one end connected to one end of said conductor and wound in the opposite direction along said conductor such that the turns of the resistance wire are substantially parallel to the turns of the conductor, the periphery of the resistance wire being greater than the periphery of the conductor such that a wiper arm of the potentiometer can make contact only with the resistance wire.

6. A winding for a potentiometer having a core; an electrical conductor of comparatively low resistance wound about said core in a first direction; a resistance wire of comparatively high resistance having one end connected to one end of said conductor and wound about said core in the opposite direction along said conductor such that the turns of the resistance wire are substantially parallel to the turns of the conductor, the periphery of the resistance wire being greater than the periphery of the conductor such that a wiper arm of the potentiometer can make contact only with the resistance wire.
